US00D658412S

(12) **United States Design Patent**
Hoyord et al.

(10) **Patent No.:** **US D658,412 S**
(45) **Date of Patent:** **** May 1, 2012**

(54) **CHAISE**

(75) Inventors: **Daniel J. Hoyord**, St. Paul, MN (US);
Joshua A. Hughes, Delano, MN (US);
Stephanie A. Grotta, Minneapolis, MN (US); **Sara L. Pedersen**, Minneapolis, MN (US)

(73) Assignee: **Target Brands, Inc.**, Minneapolis, MN (US)

(**) Term: **14 Years**

(21) Appl. No.: **29/398,370**

(22) Filed: **Jul. 29, 2011**

(51) LOC (9) Cl. **06-01**

(52) U.S. Cl. **D6/502**

(58) **Field of Classification Search** D6/334-335,
D6/353, 361-362, 367, 369-370, 500-502;
297/396-398, 410, 452.29, 452.31, 452.32,
297/452.33, 452.63

See application file for complete search history.
